UNITED STATES PATENT OFFICE.

MILES M. JACKMAN AND CHARLES W. JACKMAN, OF WATERLOO, INDIANA.

ROTARY ENGINE-VALVE.

1,331,711.

Specification of Letters Patent. Patented Feb. 24, 1920.

Application filed December 23, 1916. Serial No. 138,559.

To all whom it may concern:

Be it known that we, MILES M. JACKMAN and CHARLES W. JACKMAN, citizens of the United States, and residents of Waterloo, in the county of Dekalb and State of Indiana, have invented certain new and useful Improvements in Rotary Engine-Valves, of which the following is a specification.

The present invention relates to valves and has more especial reference to rotary valves for internal combustion engines.

The invention has for its principal object to provide a rotary valve for multiple cylinder engines having a plurality of ports formed therein in a manner such as will permit the same to successively register with the cylinder ports, whereby, the same may intake and exhaust at the proper intervals.

It is a more specific object of our invention to provide a rotary valve in which the intake and exhaust ports are provided with separate entrances or manifolds in order that fresh and spent gases may be properly conducted to and from the engine cylinders.

Among other aims and objects of the invention may be recited, the provision of a valve of the character mentioned with a view to compactness, and in which the number of parts are few, the construction simple, the cost of production small, and efficiency and operation high.

Other improvements and novel details in the construction and arrangement of the various parts of the valve will be brought out more in detail in the description to follow, which, for a clear understanding of the invention, should be considered in connection with the accompanying drawings, forming a part hereof and wherein is disclosed for the purpose of illustration, convenient and satisfactory embodiments of the invention.

In the drawings:

Figure 1 is a vertical longitudinal section through a multiple cylinder internal combustion engine, my improved valve being applied thereto;

Fig. 2 is a transverse section in detail of the valve chamber showing the arrangement of the rotary valve therein;

Fig. 3 is a fragmental end view of the valve casing with the manifold removed;

Fig. 4 is a longitudinal sectional view through the valve.

Referring now more particularly to the drawings, wherein like reference characters

designate corresponding parts throughout the several views, it may be here noted, that our improved valve is particularly adapted for use upon multiple cylinder internal combustion engines. Therefore, to fully illustrate the present improvements, we have shown in the accompanying drawings, a fragment of a multiple cylinder engine indicated in its entirety by the numeral 1, the upper portion of which is provided with a cylindrical valve receiving chamber 2, which chamber extends for the entire length of the various cylinders of the engine and communicates therewith by reason of ports 3 in the top of each of the cylinders. A cooling jacket 4 is arranged about the various cylinders of the engine and extends upwardly and about the cylindrical valve receiving chamber 2, thus, providing for means whereby a suitable cooling medium may be circulated through the chamber to maintain the cylinders and the valve receiving chamber 2 at the desired temperature. An annular chamber 5 is formed in the upper portion of one extremity of the chamber 2 and is so formed as to permit the securing of the intake manifold thereto, which manifold is indicated by the numeral 6, by means of set screws 7 or the like. Obviously, by positioning the intake manifold 6 adjacent the annular chamber 5, the same will be in direct communication with the cylindrical valve chamber 2, and consequently, permits the passage of fluid from the same thereinto, whereat, it will be properly passed into the various cylinders of the engine by the improved valve means which will be subsequently described. The opposite end of the valve chamber 2 is preferably in horizontal alinement with the intake manifold 6, and has extending from a suitable opening an exhaust manifold 8, thereby, permitting the spent gases as conveyed from the various cylinders of the engine to be exhausted into the atmosphere.

With a view toward providing means for controlling the passage of fresh and spent gases to and from the cylinders of the engine, we arrange within the cylindrical valve receiving chamber 2, a cylindrical valve 9, journaling the ends thereof within the outermost walls of the opposite engine cylinders. A plurality of circumferentially alined pairs of ports are arranged within the cylindrical valve 9 at points therealong in proximity of the engine cylinders, said

pairs of ports being arranged in relatively staggered relation, whereby, the same will be successively engaged or registered with the single ports of the engine cylinders in proper sequence. Certain of the several pairs of circumferentially alined ports as arranged within the cylindrical valve 9 serve as intake ports and are designated by the numeral 10, while others serve as exhaust ports and are in turn designated by the numeral 11. Thus, it will be understood, that upon rotation of the cylindrical valve 9, the said circumferentially alined ports will serve as means for introducing fresh charges of gas to the engine cylinders and for conveying or exhausting spent gas therefrom. A partition element 12 is arranged within the cylindrical valve 9 and extends throughout the length thereof to provide separate and distinct manifolds for the intake and exhaust ports 10 and 11. In order that the several manifolds will properly communicate with the intake portion 10 and the exhaust portion 11, the said partition is alternately twisted in opposite directions as indicated at 13, thus, providing a substantial spiral like course. By so forming the partition 12, it will be appreciated that two separate ways are arranged within the cylindrical valve 9, which, by reason of their tortuous passage communicate with the intake ports 10 and the exhaust ports 11 respectively. To insure the passage of the fresh and spent gases into and from the engine cylinders in the proper direction, the opposite ends of the partition wall are bent downwardly as indicated by the numeral 14, into engagement with the adjacent portions of the cylindrical valve 9, consequently, offering efficient closure means.

A sprocket wheel 15 is arranged upon one end of the cylindrical valve 9 and is adapted to be rotatably received within the annular chamber 5, whereupon, the sprocket chain 16, which is driven from the crank shaft of the engine at approximately one-half the speed of the latter is passed upwardly and over the various teeth thereof, thus causing the valve to be rotated at a similar speed.

To insure fluid tight connection between the cylindrical valve 9 and the side wall of the valve receiving chamber 2, there is arranged upon the said valve at points adjacent the outer portion thereof, packing 17 and 18, the latter being received within

offset seats 19 formed upon the adjacent extremities of each of the valve port side portions.

From the foregoing, it will be appreciated by workers in the art, that with our improved valve all intricate arrangements of cut off means hitherto prevalent in the art, such as puppet valves and the like will be eliminated, further, complex valve operating mechanism for actuating the said cut off means at predetermined intervals in order that the same will properly perform their functions is eliminated. It will also be understood, that by providing rotatable cut off means, the disagreeable vibration and noise commonly experienced in cut off means such as heretofore referred to is overcome.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claim is intended to cover all of the generic and specific features of the invention herein described and all statements of the scope of the invention, which, as a matter of language, might be said to fall therebetween.

We claim:—

In combination, an explosive engine cylinder having a valve chamber provided with a port, a rotary valve arranged in said chamber including a cylindrical shell having a pair of closely arranged spaced ports adapted to successively register with the cylinder port, an internal partition in the valve separating the ports therein, the portion of the shell located between and bordering upon the intake and exhaust ports being depressed to provide a seat, and packing arranged in the depressed portion of the valve preventing leakage from one port to the other between the valve and the chamber wall.

In testimony whereof, we affix our signatures hereto.

MILES M. JACKMAN.
CHARLES W. JACKMAN.
